(57) **CLAIM**

The ornamental design for a cannula assembly, as shown and described.

DESCRIPTION

FIG. 1 is a perspective view of a cannula assembly embodying our new design.

FIG. 2 is a first side view of the cannula assembly of FIG. 1;

FIG. 3 is a second side view of the cannula assembly of FIG. 1;

FIG. 4 is a third side view of the cannula assembly of FIG. 1;

FIG. 5 is a fourth side view of the cannula assembly of FIG. 1;

FIG. 6 is a top view of the cannula assembly of FIG. 1; and, FIG. 7 is a bottom view of the cannula assembly of FIG. 1. The broken lines shown herein are provided for the purpose of illustrating portions of the cannula assembly that form no part of the claimed design.

1 Claim, 4 Drawing Sheets
